UNITED STATES PATENT OFFICE

GEORGE BROWN, OF NEW YORK, N. Y., ASSIGNOR TO CRAIG AND BROWN INC., A CORPORATION OF NEW YORK

CORRUGATED STRUCTURE

Application filed September 1, 1928. Serial No. 303,382.

This invention relates to roof, skylight, side walls, canopies and area covering constructions and more particularly is directed to corrugated structures as for example, constructions using a vitreous sheet, such as glass having wire netting incorporated therein and formed with a corrugated cross-sectional contour like conventional corrugated iron and asbestos.

10 One object of the invention is to provide a novel construction method of joining corrugated sheets in overlapping relation whereby a weathertight structure is provided. Said structure when formed of glass sheet being 15 free from breakage due to accident or other causes, and in which construction the erection of coverings of the character described shall be facilitated, saving time and labor as compared with any other construction methods used heretofore.

Another object of the invention is to provide a covering construction of the character described comprising few and simple parts, which shall be easy to apply, and practical 25 and efficient to a high degree in use.

A further object of the invention is to provide an improved non-moisture absorbent spacing member for inserting between superimposed portions of corrugated sheets to readily form the novelly constructed lap joint in the improved construction embodying the invention and which shall be relatively cheap to manufacture.

Other objects of this invention will in part 35 be obvious and in part hereinafter pointed out.

The invention accordingly consists in the features of construction, combinations of elements and arrangement of parts which will 40 be exemplified in the construction hereinafter described and of which the scope of application will be indicated in the following claims.

In the accompanying drawing, in which is 45 shown one of the various possible illustrative embodiments of this invention

Fig. 1 is a perspective view of a portion of a roof or skylight construction embodying the invention.

50 Figs. 2 and 3 are cross-sectional views

taken on lines 2-2 in Fig. 1 and 3-3 in Fig. 2, respectively.

Fig. 4 is an end elevational view of one of the improved spacing members used in the novel construction embodying the invention, 55 the dotted lines indicating the position of the corrugated sheets.

Fig. 5 is a top plan view showing an improved spacing member formed with retaining means embodying the invention, and 60

Fig. 6 is a fragmentary perspective view showing an enlarged section of the improved lap joint construction.

Referring in detail to the drawing, 10 denotes a portion of a roof or skylight of vitreous corrugated sheet construction embodying the invention. Said construction is seen to comprise the novel assembly of sheets 11, preferably formed of glass having wire netting reinforcement 11^a incorporated therein 70 and formed with corrugated cross-section contour C like conventional corrugated iron and asbestos.

In the improved roof construction 10, the glass corrugated sheets 11 are mounted in 75 horizontal row A on a suitable supporting structure as shown in Fig. 1, longitudinally extending expansion joints E securing said row of sheets in position. Said joints E each include a metal cover cap 13 which overlies 80 and bridges spaced adjacent longitudinal extending crest edge portions 11^b of the sheets. An asphalt felt strip 14 is preferably provided as a lining on the under side of the cap 13 facing the sheets. Where the supporting 85 structure is of steel fabrication, the sheets 11 are supported on suitable purlins 12, comprising angle, channel or I-beam members, and the caps 13 are secured to said purlins for anchoring the sheets in position by any suitable means such as bolts 15 and clip 16. Inner strips 17 extend to underlie spaced adjacent longitudinal extending crest edge portions 11^b and are engaged by the bolts 15 for clamping said edge portions 11^b between cover caps 13 and said strips 17. One end 13^a 90 may be terminated with a hook or nose which extends over the end of the sheets 11 as shown in Fig. 3.

The edge portions 11^b of the sheets 11 are 100

spaced apart so that the body of the bolt loosely fits therebetween and the head 15^a of the bolts 15, each preferably are provided with a lead washer 18 to provide a yieldable bearing.

An asphalt strip 19 may be interposed between the top surface 12^a of the purlin 12 and the under side of the end portions of the sheets 11 to provide a cushioning base 10 part of the latter.

From Figs. 1, 2, 3 and 6, it is seen that a second row B of glass corrugated sheets 11 are mounted on the purlin structure with an end portion of the row B overlying an end portion of the row A at one of the purlins 12. The corrugations C of the superimposed portions of the sheets 11 are nested or fitted together with a row of improved spacing members serving as a filler interposed in the space 20 S between said sheets 11 to form a novel type of lap joint.

Preferably each member 20 comprises a relatively small section of the lap joint spacing filler or packing and is here shown to extend from one trough of a corrugation C over a crest portion to the next adjacent trough. It should be noted that cross-sectional shape of the space S occupied by the members 20 may not be uniform in width throughout the length thereof since the top and bottom sides of the crests and troughs of the corrugations C are of different curvature. In such cases as here shown, the members 20 are each made to conform to such unevenness and are made thicker at the ends 20^a and midportion 20^b than between such portions as shown in Fig. 4.

The improved lap joint construction is made to have relatively shallow passages P extending lengthwise thereof and relatively deep drain channels D extending transversely the length thereof. To provide these passages and channels the members 20 are formed with knife edged ledges 21 parallelly spaced on the opposite sides thereof facing the sheets 11 and the opposite edge portion 20^c of said members are chamfered.

The knife-edge ledges of the members 20 contacting with the glass sheets 11 readily permits unrestricted expansion or contraction of the joint structure. Dust has been found to settle in the passages P which automatically builds a practical and efficient seal 55 between said members and the glass sheets.

The members 20 may have one end 20^a tapered and terminated with an angle extension 22 which serves as a stop for abutting the end edge of the sheet 11 and as a guide for 60 condensation to drain moisture to the corrugated surface of the sheets. Preferably one or more of said members 20 forming a lap joint section between each pair of sheets 11 may be provided with a projecting retaining 65 means, such as wire 23. The latter has one

end anchored in the body of the member 20 and the other end adapted to be bent up for gripping the edge of the overlying sheet whereby the superimposed sheets are retained in position during erection before the bolts are fastened and serving as a supplemental anchorage for the sheet. The members 20 are preferably made of a non-absorbent material such as hard rubber, pheno-condensate products, metals and particularly ductile and flexible material as for example molded lead, alloys thereof or other metals having like properties. The wire 23 may be formed of steel, copper, brass or bronze and is anchored to the member 20 in any suitable manner as 70 by embedding said wire during the molding of the latter.

By using the materials in the parts forming the improved lap joints and the members 20 as described above so as to provide the passages P and the drain channels D air circulation is permitted through the joints and along the inner surface of the sheets 11. Moisture due to condensation and capillary attraction on the sheets 12 and in and about the joints is 75 thus eliminated or drained off. In installation constructed as above described it has been satisfactory to extend the members 20 for only part of the width of the space S, as shown in Fig. 3, so that said member can 80 be made relatively small and cheap.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all 105 matter herein set forth or shown in the accompanying drawing is to be interpreted as illustrative and not in a limiting sense.

Having thus described my invention, I 110 claim as new and desire to secure by Letters Patent:

1. In a construction of the character described, a pair of corrugated sheets, positioned with their ends in overlapping relation having a space therebetween, and a filler comprising a plurality of identical members interposed between the lapped portions to form a joint, said members having their adjacent edges spaced from each other and forming drainage channels in the troughs of said corrugated sheets.

2. In a construction of the character described, a pair of vitreous corrugated sheets positioned with their ends in overlapping relation having a space of varying thickness therebetween, and a non-absorbent filler positioned in the space between the lapped sheet portions, said filler material being preshaped

to have a thickness corresponding to the contour of said space.

3. In a construction of the character described, a pair of corrugated sheets positioned with their ends in overlapping relation having a space therebetween and a non-absorbent filler interposed between the lapped sheet portions, and spaced upstanding ledges on said filler contacting said sheets 10 extending lengthwise the joint and transversely the sheet corrugations, said members having means to provide drain channels extending through the joint.

4. As an article of manufacture a filler 15 member adapted to be interposed between spaced overlapping portions of a pair of corrugated sheets to form a joint comprising a non-absorbent packing, preshaped to correspond to the cross-sectional curved con- 20 tour of the space between said sheet portions and extending from a point spaced from the center of one trough of a corrugation over the crest portion thereof to a point spaced from the center of the next adjacent trough, where- 25 by a drainage channel will be formed between the adjacent filler members when so inter- posed.

In testimony whereof I affix my signature.
GEORGE BROWN.
